AMMUNITION

Joseph G. Cadham, Hampstead, Quebec, Canada,
assignor to Canadian Industries Limited, a corporation of Canada

Application June 11, 1940, Serial No. 339,862
In Canada March 29, 1940

3 Claims. (Cl. 102—42)

Shot shells as heretofore produced on the North American continent have been closed by the insertion of a "top wad" over the shot charge. This top wad consists of a circular piece of coated cardboard having a diameter approximately the same as the internal diameter of the shot shell tube. This top wad is maintained in position by turning the open end of the shot shell tube inwardly and downwardly through 180° to form a U bend, the free leg of the U pressing against the top wad and thereby maintaining it in position. This type of closure is hereinafter referred to as a "standard roll crimp." It has been the general practice to impregnate the shot shell tube with wax at some stage prior to the loading operation to improve the waterproofing of the shell though in some instances unwaxed paper tubes have been used. Such shot shells, whether of waxed or unwaxed tubing, have generally been further waterproofed by immersion of the shell, after completion of the standard roll crimp, in a lacquer solution.

Waterproofing in shells made according to the foregoing procedure has generally been found to be quite adequate. The ballistics of such shells, however, have often been found to be very erratic and "blown" patterns, particularly, were often produced. These blown patterns have been found to be caused by the emergence of the top wad with the charge of shot from the gun barrel and causing an accentuated spreading of the shot in such a manner that an irregular area, substantially devoid of shot, is formed within the charge circle at the target.

According to my invention, I produce a shot shell in which the shot pellets are retained within the shell by turning over the upper portion of the shot shell tube itself, whereby the over-shot wad formerly considered necessary in the production of shot shells is eliminated.

An object of my invention is to produce a shot shell in which "blown" patterns are materially reduced or completely eliminated.

A further object is the production of a shot shell which is substantially waterproof under the conditions to which it is normally subjected.

A still further object is the production of a shot shell in which better uniformity of ballistics is obtained.

The closing of a shot shell by turning over the upper or anterior end of the cartridge is in itself not new. United States Patent No. 929,866, issued August 3, 1909, to George Meadows, proposed this method of closing a shot shell, and outlined the numerous advantages which would be obtained by such a closure. Garkovenko and Fighiera, French Patent No. 593,010, also proposed a similar closure in conjunction with a particular method for loading the powder charge. Robert L. Wheeler, Canadian Patent No. 259,581,

again proposed this turn-over closure method for sealing a shot shell and this method was used in conjunction with a particular way for enveloping the shot charge as well as having a particular over powder wad. However, though this type of closure has been known for a number of years it has never received commercial development because of the erratic ballistics which were obtained in shot shells produced according to this prior art and because no means has been devised in which shells having this type of closure could be made completely waterproof.

These defects are overcome by my present invention, which will be more clearly understood by reference to the accompanying drawing in which Fig. 1 shows partly in cross section the shell completely loaded and ready for the closure operation of my invention. Fig. 2 shows the same shell in which the turning over of the body top has been partially completed, and Fig. 3 shows the shell with the body top turned over to its final position. Fig. 4 shows the upper part of a shell in cross section having a disc of plastic material outside the turned over closure and flush with the end of the shell, substantially in accordance with the process of my invention. This is illustrated in perspective in Fig. 5. Fig. 6 shows the upper end after discharge, of a shell produced according to my invention. The irregular areas 12 indicate where the plastic material has adhered to the shell and has been torn away by the discharge of the shot. Fig. 7 illustrates the tool which is used to produce the partially completed turn-over closure shown in Fig. 2. This tool serves to pleat the turn-over portion of the shot shell tube and is adapted to slide vertically in a guide (14 of Fig. 7A) which is of such a diameter that easy entry therein of the shot shell of Fig. 1 is permitted. Fig. 7A is a view of the combined tool and guide with the guide being shown in cross section.

Fig. 8 illustrates the tool for the completion of this turn-over as shown in Fig. 3. This tool consists of a rotating member having a vertical reciprocating motion and is used for the operation succeeding the one performed by the tool as shown in Fig. 7A. This tool also operates in a guide 17 of such diameter that easy entry of the shot shell of Fig. 2 is permitted. Fig. 8A is a view of the finishing tool and die with the die shown in cross section.

In Fig. 1 the shell consists of a body 1, shot charge 2, over powder and filler wads 3, powder charge 4, base wad 5 and battery pocket and percussion cap 6, all in accordance with present practice for loading shot shells.

The shot shell as in Fig. 1 is placed in the machine in which the die shown in Fig. 7 is adapted to vertical up and down motion, the die is brought down a controlled distance over the open end of

the shot shell, and sufficient pressure is applied to form the pleats 7 as shown in Fig. 2 and the die shown in Fig. 8A, adapted to be mounted in the same machine or another machine is then brought down over the pleats 7 of Fig. 2 and with a rotary motion further depresses the pleats until the surface thereof is approximately at right angles to the axis of the shell. The face of the tool is slightly crowned as shown at 18 in Fig. 8, and the diameter is slightly less than the interior diameter of the shot shell tube. The rotary motion of the die of Fig. 8 tends to form a slight shoulder at the edge of the shot shell body as shown at 9 in Fig. 3, thus leaving a slight depression in the top surface of the closure.

It will be readily seen that in bringing the frustro conical sections of 7 of Fig. 2 into the position shown at 8 in Fig. 3, a small aperture 10A is left at the axis line of the shell at the apex of the pleats. This aperture as well as the creases between the segments 8 are then completely sealed by spinning into the depression above referred to, a plastic composition which forms a disc as shown at 10 in Fig. 4.

This plastic material is sufficiently cohesive so that no breaking down will occur and no chipping off of the portions of the disc will result in the relatively severe action to which the shell is subjected in shot guns and particularly in so-called pump guns, repeating or autoloading guns, or in other rough treatment to which shells are sometimes subjected. At the same time the disc may be sufficiently friable that substantially complete disintegration occurs on discharge of the shot. This disintegration may be desirable since if the disc was sufficiently cohesive to leave the shotgun barrel as a unit and not sufficiently cohesive that segments are wholly retained as hereinafter described, the effect would be similar to the use of a top wad and blown patterns might result. This ability of the disc to disintegrate on discharge of the shot shell may be said to represent at one extreme, a very desirable physical characteristic of the sealing disc. On the other hand, and at the other extreme, if the adhesion between the particles of the material forming the disc and the adhesion of the disc to the waxed or unwaxed paper surface of the shot shell body is materially increased, this ability of the disc to disintegrate on discharge of the shot shell will thereby decrease in inverse ratio to the increase in adhesion. Then this adhesion has reached such a point that on discharge of the shot shell the disc is ruptured and all the segments of the disc are wholly and tenaciously retained on the paper of the shot shell body, this may be said to represent the other extreme of the desirable physical characteristics of the disc. In the preferred form of the invention one or the other of these extremes is maintained. Adhesion between the particles of the material should not, however, exceed the adhesion of the mass to the paper. Other desirable physical characteristics are that the disc shall set to a relatively hard compact mass in a relatively short time and that in setting there will be substantially no contraction of the material. This absence of contraction is particularly important since with only a relatively small contraction, this sealing means would fail in its moistureproofing function. The appearance and ballistics of the shell would also be adversely affected by such contraction. Failure of the shell to function satisfactorily in pump and similar guns might also occur.

A further desirable physical characteristic of 75

the material is that it shall be adaptable while in the plastic state to be spun into position and that the finished surface after spinning in shall be sufficiently smooth to show clearly any printing thereon.

5 The required amount of plastic material may be applied by any means found adaptable such as by ejection of the plastic material from a tube or other ejection apparatus. After the 10 disc of plastic material has dried the completed shell is preferably immersed in a lacquer solution.

I have found that the material used for plastic compositions suitable for my invention is preferably finely divided carbonaceous material such as

15 wood flour with or without the addition of other finely divided materials such as diatomaceous earth together with binders and sufficient solvent to bring the other materials to a dough-like mass. As examples of carbonaceous materials other than wood flour, ground ivory nut meal, ground cocoanut shells, bagasse pith and ground corn stalks may be given. The binder may be a solution of a cellulose ester or ether or of any natural 20 or synthetic resin having a softening point higher than 65° C. or mixtures thereof. The additional solvent required to bring the mixture to a dough-like consistency may be selected from any of the solvents compatible with the binder solution. 25 When the material is to be used on a wax impregnated shell one of the solvents contained in the mixture should have sufficient solvent action on the wax that adequate penetration of the wax surface is obtained in order to enhance the adhesion of the material to the shot shell body.

30 Examples of suitable plastic compositions for carrying out my invention are as follows:

	Parts
Wood flour	2.5
Kieselguhr	2.5
Binder solution	10.0

40 The binder solution given in Example 1 is made up as follows:

	Per cent
Nitrocellulose	9.6
Ester gum	20.5
Castor oil	4.2
55 Amyl acetate	3.3
Ethyl acetate	26.0
Ethyl alcohol	13.0
Textile spirits	16.4
Toluol	7.0
	100.0

60 Textile spirits is an aliphatic fraction from petroleum having approximately the same evaporation rate as benzol.

	Parts
70 Wood flour	2.5
Kieselguhr	2.5
Castor oil	1.0
Rosin solution (80% total solids)	1.0
Solution of polymerized methyl methacrylate (20% total solids)	7.5

3

Kieselguhr	Parts
Wood flour	2.5
Castor oil	2.5
Rosin solution (80% total solids)	0.5
Polyvinyl acetal resin solution (25% total solids)	1.0

The following comparative tests were carried out on shot shells having the standard roll crimp and top wad, shot shells recessed in accordance with the prior art, and shot shells produced according to the present invention. (All of the shells used in all tests were wax impregnated in the tubular paper portions.)

TEST

Results

1. Velocities, pressures and patterns as obtained in a standard test gun, 10 shells in each test. All shells tested had a standard trap load containing $1\frac{1}{4}$ oz. of $7\frac{1}{2}$ chilled shot; approximately 450 pellets per shell.

Shell	Velocities, f.s.	Variation		Pressure, lbs./sq. in.	Patterns in 30" circle at 40 yds.			
		Extreme, f.s.	Mean, f.s.		Average		Mean variation from average pellets	
					Pellet count	Per cent		
Standard roll crimp with top wad and lacquer finished	841	43	12.9	9,420	268	59.6	20.9	
Folded recessed crimp according to prior art. Not lacquer finished	844	38	8.6	8,760	289	64.3	11.7	
Crimp according to my invention. Lacquer finished	853	26	6.0	9,260	309	68.7	13.2	

5

Kieselguhr	Parts
Wood flour	2.5
Castor oil	2.5
Rosin solution (80% total solids)	0.5
Phenol-formaldehyde resin solution (30% total solids)	1.0
	7.5

6

Kieselguhr	Parts
Wood flour	2.5
Castor oil	2.5
Rosin solution (80% total solids)	0.5
Cellulose acetate solution (15% total solids)	1.0
	12.5

As an example of a suitable solvent mixture the following may be given:

Butyl acetate	Per cent
Ethyl acetate	35.00
Synthetic amyl alcohol	35.00
Denatured alcohol	3.20
	26.80
	100.00

In addition to the synthetic resins given in the above examples, other resins such as gum copal, polystyrene, shellac, urea-formaldehyde, indene-coumerone and "Glyptal" resins have been used.

The wood flour used in the above examples is finely ground, for example, to pass a 120 mesh sieve or finer.

The kieselguhr used is of the commercial grade.

Where a rosin solution is specified, this may be a proportion of ordinary rosin or colophony, or ester gum, in a suitable solvent or solvent mixture.

Where solutions of other synthetic resins are specified, these may be a proportion of the synthetic resin in any suitable solvent such as a low-boiling organic acetate.

It should be noted in the above test that in the shells according to my invention there was a slight increase in velocity and a substantial increase in the number of pellets within the 30" circle. The reduction in the mean variation in velocities and the reduction in the mean variation from the average number of pellets is also clearly indicated.

Thus a marked improvement in all desirable characteristics is shown in the above test when using shot shells produced according to my invention.

Having thus described my invention, what I claim is:

1. A shot shell having a wax-impregnated body and integral with said body an end closure comprising a plurality of inwardly folded segments forming a depression slightly within the plane of the end of the body and a disc of plastic self-hardening waterproofing composition substantially filling said depression and in adhesive engagement with said segments, the said plastic composition comprising a carbonaceous material, a diatomaceous material, a binder and a solvent for said binder which is likewise a solvent for the body-impregnating wax.

2. A shot shell having an end closure integral with the body thereof, the said end closure comprising a plurality of inwardly folded segments forming a depression slightly within the plane of the end of the body, and a disc of a plastic, waterproofing composition consisting of wood flour, kieselguhr and a binder solution substantially filling said depression and in adhesive engagement with said segments.

3. A shot shell having an end closure integral with the body thereof, the said end closure comprising a plurality of inwardly folded segments forming a depression slightly within the plane of the end of the body, and a disc of a plastic waterproofing composition consisting of wood flour 2.5 parts, kieselguhr 2.5 parts, binder solution 10 parts.
